[57] **CLAIM**

The ornamental design for a packaging container for light bulbs or the like, as shown.

DESCRIPTION

FIG. 1 is a top perspective view of a packaging container for light bulbs or the like showing my new design;

FIG. 2 is a front elevational view;

FIG. 3 is a top plan view;

FIG. 4 is a top plan view with the lid removed;

FIG. 5 is an elevational view looking from the left of FIG. 2;

FIG. 6 is a rear elevational view;

FIG. 7 is an enlarged top perspective view with the lid in an open position; and

FIG. 8 is an enlarged vertical sectional view taken on a line extending between the front and rear.
